UNITED STATES PATENT OFFICE.

ANTHONY O'BRATE, OF ENID, OKLAHOMA TERRITORY.

FLYING-MACHINE.

No. 867,525.

Specification of Letters Patent.

Patented Oct. 1, 1907.

Application filed December 21, 1906. Serial No. 348,991.

To all whom it may concern:

Be it known that I, ANTHONY O'BRATE, a citizen of the United States, residing at Enid, in the county of Garfield and Territory of Oklahoma, have invented 5
5 Improvements in a Flying-Machine, of which the following is a specification, reference being had therein to the accompanying drawings.

My invention relates to certain new and useful improvements in flying machine, and the objects of my 10
10 invention are to improve the means for maintaining the equilibrium of the machine, means for guiding and turning the machine, means for driving the machine and other details, as will be hereinafter pointed out.

With these objects in view my invention consists in 15
15 certain constructions, combinations and arrangements of parts, the preferred form of which will be first described in connection with the accompanying drawings, and then the invention particularly pointed out in the appended claims.

20 Referring to the drawings wherein I show one embodiment of my invention and wherein the same part is designated by the same reference numeral wherever it occurs, Figure 1 is a perspective view of a flying machine constructed in accordance with the preferred 25
25 form of my invention; Fig. 2 is a view of the forward section of the machine looking from the rear; Fig. 3 is a top plan view showing the aeroplanes in dotted lines; Fig. 4 is a detail view showing the arrangement of the forward rudder; Fig. 5 is a detail perspective view of 30
30 the connection between the bars of the main frames of the aeroplanes; Fig. 6 is a side elevation of one of the side propellers; Fig. 7 a detail perspective view of parts of the propeller; Fig. 8 is a detail view of a pair of connected blades of the propeller; Fig. 9 is a 35
35 view similar to Fig. 2, showing however a modified construction; Fig. 10 is a detail view showing a portion of the connection illustrated in Fig. 9 enlarged.

11 designate a pair of rods to which are secured the aeroplanes 2, and 3, 3 are balloon sections, secured 40
40 between the aeroplanes in the manner fully described in my allowed application No. 302,821, filed February 24, 1906.

4 designates a series of triangular braces connected together at their bases by means of the bars 45
45 5, 5, the triangular braces and bars forming two frames, one for the forward aeroplane and one for the after. The bars 5 at their inner end are connected together by means of the shaft 6 passing through eyes 7 formed in the adjacent ends of the bars 5. At the third 50
50 angle of the triangle braces 4 are provided bearings 8, in which are loosely mounted the rods 1, supporting the aeroplanes.

The adjacent ends of the rods 1 are connected together by means of the connection shown in the detail in Fig. 5, this connection consisting of a pair of 55
55 arms 9 pivoted at 10 to one of the rods 1, and extending out on each side thereof, and a second pair of arms 11 pivoted at 12 to the other rod, and extending outwardly therefrom, the free ends of the arms of the opposite rods being secured together by means of the 60
60 connecting links 13 in which they are pivoted by means of the pivots 14.

16 designates a car in which the power mechanism is mounted and which carries the operator. This car is provided with a forward pair of wheels 17 and an 65
65 after pair of wheels 18, the after wheels being preferably carried by arms 19 to which is provided a lever 20, whereby they may be raised and lowered in relation to the car to give the machine the desired inclination, as fully described in my application referred to. The 70
70 car is supported from the shaft 6 by a pair of rods 21 secured to about the central section of the car. These rods or hangers loosely engage the shaft 6, which construction is also fully described in my aforesaid application. 75

22 designates a pulley mounted in the car to which power is applied from any suitable source, not shown. 23 is a belt running from the pulley 22 to pulley 24, mounted upon the shaft 6, whereby the shaft is rotated. 25 designates a second belt running from the 80
80 pulley 22 to the pulley 26, from which is driven the propeller 27 constructed as fully shown and described in my above mentioned application.

28 designates a cord secured at each end to the links 13 and running around a wheel 29 mounted on a cross 85
85 brace 30 extending between the supporting links 21. By this construction the aeroplane can be tilted in relation to the car toward the right or toward the left, and whereby the machine is steered.

31 designates a cord extending from one of the triangular braces 4 of the forward section to a wheel 32, and 90
90 33 designates a similar cord extending from one of the triangular braces 4 of the after section of the frame to a wheel 34. By these cords the aeroplanes can be set at an angle to each other for the purpose fully described in my application above referred to.

35 is a balancing plane pivotally connected to arms 36 extending upwardly from the rear of the car, and 95
95 37 is a lever pivoted on the car and connected to an arm 38 on the balancing plane by means of a link 39, whereby the position of the plane may be adjusted for the purpose fully described in my above referred to application. 100

40 designates a pair of propellers mounted on the

ends of the shaft 6. These propellers are preferably constructed as shown in detail in Figs. 6, 7 and 8. Referring to these figures, 41 are a pair of rims spaced apart and secured to the shaft 6 by means of the spokes 42. 43 are a pair of rims secured to the shaft 6 by spokes 44. 45 are shafts rotatably mounted in the rims 40 and the rings 43. These shafts are arranged in pairs around the rims as shown in Figs. 6 and 8. 46 are rectangular blade sections secured to the shafts 45, 10 the blade sections being secured to the shafts at one side of their central line, as indicated in Figs. 6 and 8. These sections are connected together by links 47 pivoted at 48 to the sections, whereby the sections move in unison. At the lower end of each shaft 45 I provide 15 a cam engaging arm 49, in the outer extremities of which are antifriction rolls 50, these rolls being adapted to contact with a cam section 51, formed upon the outer bearings 52 of the shaft 6, said bearings being supported by the braces 53 extending from the supports 21.

From the above described construction it will be seen that the cams are held stationary while the shaft carrying the propellers rotates, and that while the propellers are in the position in which the arms 49 engage 25 the cams, they will be held at right angles to the direction of rotation of the propeller, as indicated in Fig. 6 while during the remainder of the rotation they will be free and can turn and feather, due to the fact that the blades are not centrally mounted on the shaft, and 30 consequently there is a greater pressure on one side of the shaft than on the other.

It will be understood that in the present form of my invention the steering of the machine is accomplished by tilting the aeroplane to one side in relation to the car, which is effected by means of the wheel 29. Tilting the aeroplane to the right causes the machine to veer to the right, and tilting it to the left causes the machine to turn to the left. In order to assist in thus steering the machine I provide a forward 35 aeroplane 54 which is carried by a shaft 55 mounted in a bearing 56 carried by supporting braces 57, extending down from the forward portion of the forward section of the frame. This aeroplane, as will be seen is mounted at an angle to the plane of the main aeroplane section 2. 58 designates a pair of arms extending out on opposite sides from the shaft 55, and 59 designates a pair of arms extending out from opposite sides of the rod 1. 60 are cords connecting the ends of the arms 59 to the ends of the arms 58. From this 40 construction it will be seen that when the main aeroplanes are tilted, the aeroplane 54 will be correspondingly tilted, which will give increased turning power to the machine. 61 designates a rudder mounted on the shaft 62 at the stern of the machine, the shaft 62 being mounted in a bearing 63 supported by braces 64 at the stern of the after section of the frame. At 45 its upper portion the shaft 63 is provided with an arm 65 having a slot 66 therein and 67 is a rod fast to the rod 1 which extends down and enters the slot 66. 50 From this construction it will be seen that the rudder will be turned upon the tilting of the aeroplane in a direction to assist in the turning movement.

Referring to Fig. 9, I have shown a construction whereby the equilibrium of the machine is automatically controlled. In this construction, a pair of arms 65 68 extend out from opposite sides of the shaft 1. By means of cords 69 the extremities of these arms are connected to the extremities of a bar 70 from which extends a stub shaft 71 having fast thereon a corrugated or milled collar 72. 73 designates a pair of arms 70 pivoted at 74 to the bar 70. These arms 73 having their portion 75 above the bar 70 connected by a spring 76, and they also have the portions 77 extending on opposite sides of the roughened collar 72, the inner faces of these extensions being roughened to engage 75 with the collar. To the extremities of the arm 73 I secure, by cords 78, a weight 79. By this connection it will be seen that when the machine tilts in one direction it will cause weight to swing toward the lower side, which will cause the arm 73 on the opposite side 80 to move downward, turning the corrugated collar 72 which, through the arm 70, will tend to return the aeroplane sections to normal position. The corrugated collar and arm 73 are for the purpose of adjusting the relation between the arms carrying the weight and 85 the aeroplanes, whereby the position of the aeroplanes, when the weight is immediately below the shaft, can be varied. The construction described also permits the arms being raised from the shaft by merely raising the weight, should it be desired to take the machine 90 out from under the control of this automatic means.

From the above description it is believed that the operation of my machine will be apparent without further description.

While I have described what I believe to be the 95 preferred form of my invention, I desire to have it understood that many changes may be made in the form, construction and arrangement of parts without departing from the spirit of my invention.

What I claim as new and desire to secure by Letters 100 Patent is

1. In a flying machine the combination with a frame having a shaft journaled therein, of a pair of aeroplanes secured to the shaft in fixed relation to each other, an aeroplane extending outwardly from each side of said shaft, a car supported from said frame and connections controlled from the car, whereby said aeroplanes may be tilted to steer said machine laterally.

2. In a flying machine the combination with a frame having a shaft journaled therein, of a pair of aeroplanes secured to the shaft in fixed relation to each other, an aeroplane extending outwardly from each side of said shaft, means permitting the tilting of the aeroplanes in relation to the frame, a rudder mounted at the rear of said frame, connections between said rudder and said shaft whereby the rudder will be shifted in accordance with the tilt of said aeroplanes, a car suspended from said frame and connections controlled from the car whereby the aeroplanes may be tilted to steer said machine laterally.

3. In a flying machine the combination with a frame, of a pair of aeroplanes one extending outwardly from each side of said frame, means permitting the tilting of the aeroplanes in relation to the frame, a third aeroplane journaled on the frame and below said pair of aeroplanes, 115 said third aeroplane being mounted at an angle to the plane of said pair of aeroplanes and connections between said pair of aeroplanes and said third aeroplane whereby said aeroplanes will all tilt in unison to steer said machine laterally.

4. A propeller for flying machines comprising a shaft, a rim, a second rim surrounding the first rim, spokes connecting said two rims and said shaft together, a plurality of shafts journaled between said rims, propeller blades mounted on said last mentioned shafts, the surface of said blades on one side of said shafts being greater than the surface on the other, and means stationarily supported adjacent to the inner ends of said last mentioned shafts for holding the blades at right angles to the plane of rotation during a portion of their rotation only, whereby the blades will be permitted to turn into a plane parallel to the plane of rotation during the remainder of their movement by the unequal pressure on opposite sides of the blades carried by the shafts.
